CAN DIVIDER MECHANISM

Charles E. Walters, Vancouver, British Columbia, Canada, assignor to American Can Company, New York, N. Y., a corporation of New Jersey

Application October 23, 1956, Serial No. 617,758

11 Claims. (Cl. 198—31)

This invention relates to a can divider and more particularly to a mechanism for directing cans from one supply line into a plurality of can lanes, or paths which lead to can treating stations.

In can or container making and filling and closing practices where operations are performed on cans and can bodies, for example where can bodies are fitted with an end closure, and the resulting can or container filled with a product and sealed and labeled, a plurality of identical operating stations or machines such as closing machines or labeling machines are used in conjunction with a single source of supply of cans or bodies. In order to supply a continuous flow of cans to these multiple stations or machines, a can divider is employed wherein cans are directed from a source along a supply line and divided into a plurality of paths or lanes which then supply the cans to the individual stations or machines. Accordingly, it is an object of this invention to provide an improved can divider.

It will be appreciated that as cans are moved to treating stations, it is possible for a jamming condition to exist at one of these stations thereby causing the cans to back up in its supply lane. Such a back up or jam might cause serious damage to automatic machinery and also to the cans unless the flow of cans to that lane is promptly interrupted. It is therefore a further object of this invention to provide an improved can divider wherein means is provided for interrupting the flow of cans to any can lane when a jam exists therein.

It is a further object of this invention to provide a mechanism which while interrupting the flow of cans to a jammed lane serves the dual function of automatically diverting cans intended for the jammed lane into a normally operative can lane.

It is a still further object of this invention to provide a mechanism which will interrupt the flow of cans from the supply line when a plurality of the supply lanes are jammed.

Numerous other objects and advantages of the invention will be apparent as it is better understood from the following description, which, taken in connection with the accompanying drawings, discloses a preferred embodiment thereof.

Referring to the drawings:

Figure 1 is a top plan view of a can supply line embodying the instant invention, with parts broken away;

Fig. 2 is a side view of the supply line shown in Fig. 1;

Fig. 3 is a top plan view similar to Fig. 1, showing certain of the parts in position for a particular can flow condition;

Fig. 4 is a schematic wiring diagram of the electrical apparatus used in the device; and

Fig. 5 is a side view of a portion of a can runway showing a can jam condition.

Briefly this invention relates to a can divider mechanism having a plurality of deflector gates including automatic control mechanism therefor, with each gate being operable in conjunction with a drag plate and a can lane

2

to define, when the deflector gate is in its normal position, one side of a throat for a corresponding can lane, and when in its operative position a block for its corresponding throat and a deflector guiding cans into a different

5 throat.

As a preferred or exemplary embodiment of the instant invention the drawings illustrate a can divider 2 (Fig. 1) utilized in conjunction with a can supply line 4, a drag plate 6 and a pair of can lanes 8, 10, extending from the drag plate. The divider 2 comprises a deflecting horn 12, a pair of deflecting gates 14, 16 and suitable control mechanism therefor.

In normal operation cans are carried along the can supply line 4 by a belt or cable conveyor 18 which frictionally urges the cans onto and across the drag plate 6.

15 The latter is defined in width, in the preferred embodiment, by the deflecting gates 14, 16, which in turn are pivotally supported on the drag plate by spaced pivots 20, 22 for movement from a normal to a deflected position. 20 In their normal position, the deflecting gates 14, 16 are spaced apart in substantially parallel relationship a distance which is less than the diameter of two of the cans which are being processed, but greater than the diameter of one of those cans thereby permitting or forcing the 25 cans to assume staggered positions on the drag plate 6 in the form of two rows having their centers displaced less than one can diameter, as shown in Fig. 1, and with each row of cans abutting one of said deflecting gates.

As the rows of cans traverse the drag plate 6, under 30 the driving force of the cable 18, they come into contact with the dividing horn 12 which in turn, directs the cans into a lane 8, 10 corresponding to the row in which the can has been traveling.

In this respect it will be noted that an opening or throat 35 19, 21 of each can lane is defined by the horn 12 and a corresponding one of the deflecting gates 14, 16, respectively.

In normal operation, as a can is diverted from drag plate 6, through a throat and into a supply lane, it is 40 twisted 90° in a tilt chute or twister unit 24, 26 respectively, aligning the can into a sidewise rolling position for gravity flow to some selected can station or machine (not shown). Enroute along the can lanes, each can rolls over a balance beam 28, 30 located one in each of the 45 lanes 8, 10, respectively.

As described completely in United States Patent No. 1,916,255, issued July 4, 1933, to W. K. Cabot and assigned to the same assignee as that of the present invention, a balance beam 28, 30 is inoperative under the conditions of normal can flow in its respective lane, but in case of a can jam, such as that shown in Fig. 5, the balance beam 30 is tilted about a pivot point 31 to complete a circuit through an electric switch 35 to serve a hereinafter defined purpose. Balance beam 28 has a corresponding pivot point 29, and electric switch 33.

With reference again to the deflecting gates 14, 16, each gate is illustrated as being connected with a power driving means, such as a solenoid 32, 34 respectively. Each solenoid, when energized, pushes against the side of its corresponding deflecting gate to pivot the same about its pivot point 20, 22 into a deflected position as shown for gate 14 in Fig. 3. In the deflected position, because of a jam in its corresponding lane, the gate has been moved across the throat of its corresponding lane towards the horn 12. Enroute to this deflected position, the gate exerts a lateral thrust on the cans in the adjacent row, squeezing them into alternate positions in the opposite row, thereby diverting all the cans on the drag plate 6 into alignment with the throat of the opposite lane until the jam has been relieved.

65 70 It will be noted particularly that with the unique arrangement of the deflecting gates 14, 16 acting as side

walls of the drag plate 6 (and being spaced apart greater than one can diameter but less than two) it is impossible for two cans to reach a dead center point abutting position to block the operation of the deflecting gates, therefore the lateral thrust of the deflecting plate aligns all of the cans on the drag plate for travel into the can lane which remains open or unobstructed.

With reference to the schematic wiring diagram (Fig. 4) a power supply is indicated by the generator G. A current path is established by the conductors 36, 38 from the generator G to one side of the electrical switches 33, 35, respectively. The circuit is continued from the other side of the switches 33, 35 through the coils of solenoids 32, 34 by the conductors 40, 42, respectively. The circuit is completed back to the generator by the common conductor 44.

In normal operation (e. g. no can jam) the balance beams 28, 30 are not tilted and, therefore, switches 33, 35 are open, and the solenoids are deenergized. In the event of the operation of one of the balance beams, for example the balance beam 28, current would flow from the generator G along the conductor 36 to the contact 33-2, normally open but now closed, through the contact, along the conductor 40 to the solenoid 32 and back along the common wire 44 to the generator G. This complete circuit energizes solenoid 32 and pivots the deflecting gate 14 about its pivot point 20 to its deflected position shown in Fig. 3.

By corresponding circuit, if the balance beam 30 is operated by a cam jam in the lane 10, then the contacts 35-2 would be closed to energize the solenoid 34 and move the deflecting gate 16 to its deflected position. The solenoids 32, 34, when energized remain energized until the cam jam is relieved whereupon the balance beams are restored to their rest or normal positions. Then tension springs 37, 39 respectively restore the deflecting gates to their normal positions.

It will be appreciated that if either of the deflecting gates 14, 16 is moved to its deflected position, can flow will be continued with the entire supply being directed into the can lane opposite the deflecting gate that has been operated. However, if there is a concurrent can jam in both can lanes 8, 10 whereby both balance beams 28, 30 are tilted, then it is apparent that the supply of cans from the supply line 4 should be interrupted. To accomplish this objective, a stop solenoid 46 is so positioned with respect to the can supply line 4 that when the solenoid is energized, its core 48 will be moved up into the can line, or the core will operate other suitable mechanism such as that shown in Fig. 9 of United States Patent No. 1,916,255, previously referred to and thereby cut off the flow of cans from the supply line 4. To insure this result, the balance beam operated switches 33, 35 are provided with a second set of contacts 33-4 and 35-4 respectively, which are in circuit with the coil of solenoid 46. Accordingly, in the event of a concurrent double lane can jam, a circuit is established from the generator G (Fig. 4) along conductor 49 through the coil of solenoid 46 and along conductor 50 through the normally opened, now closed, contacts 35-4 along the conductor 52, through the normally open, now closed, contacts 33-4, back along conductor 44 to the generator G thereby establishing a circuit to solenoid 46, operating the same to stop the flow of cans in supply line 4.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a mechanism having means for feeding a plurality of curvilinear objects along a supply line, a divider for

providing plural flow paths for said objects comprising a drag platform positioned to receive said objects fed from said supply line, a pair of supply lanes extending from said drag plate, a dividing horn interconnecting adjacent sides

- 5 of said supply lanes, a pair of deflecting gates, means pivotally supporting the same in a rest position on said drag plate to define lateral guides for said drag plate for guiding said objects fed by said supply line normally into each of said supply lanes, throat means for each supply lane defined by said dividing horn and a corresponding one of said deflecting gates respectively, individual power means for said deflecting gates for moving the same from a rest position to a deflected position wherein said gate is moved towards said dividing horn to block the entrance 10 throat of its corresponding supply lane, and means responsive to a predetermined condition in one of said supply lanes for actuating said power means for the corresponding deflecting gate.

2. In a mechanism having means for feeding a plurality of curvilinear objects along a supply line, a divider for providing plural flow paths for said objects comprising a drag platform positioned to receive said objects fed from said supply line, a pair of supply lanes extending from said drag plate, a dividing horn interconnecting adjacent sides of said supply lanes, a pair of deflecting gates, means pivotally supporting the same in a rest position on said drag plate to define lateral guides for said drag plate for guiding said objects fed by said supply line normally into each of said supply lanes, throat means for 15 each supply lane defined by said dividing horn and a corresponding one of said deflecting gates respectively, individual power means for said deflecting gates for moving the same from a rest position to a deflected position wherein said gate is moved towards said dividing horn to block the entrance 20 throat of its corresponding supply lane, and means to provide a slanted lateral guide to direct the flow of all objects from said drag platform into said opposite throat, and means responsive to a predetermined condition in one of said supply lanes for actuating said power means for the corresponding deflecting gate.

3. In a mechanism having means for feeding a plurality of curvilinear objects along a supply line, a divider for providing plural flow paths for said objects comprising a drag platform positioned to receive said objects fed from said supply line, a pair of supply lanes extending from said drag plate, a dividing horn interconnecting adjacent sides of said supply lanes, a pair of deflecting gates, means pivotally supporting one end of each of said gates on said drag plate in a rest position with said gates 25 having a parallel relationship spaced apart a distance less than the diameter of two of said objects but greater than the diameter of one of them thereby defining lateral guides for directing said objects fed by said supply line into each of said supply lanes, throat means for each 30 supply lane defined by said dividing horn and the free end of a corresponding one of said deflecting gates respectively, individual power means for said deflecting gates for moving the same from said rest position to a deflected position wherein the free end of said actuated gate is moved towards said dividing horn to block the entrance 35 throat of its corresponding supply lane, and means responsive to a predetermined condition in one of said supply lanes for actuating said power means for the corresponding deflecting gate.

4. In a mechanism having means for feeding a plurality of curvilinear objects along a supply line, a divider for providing plural flow paths for said objects comprising a drag platform positioned to receive said objects fed from said supply line, a pair of supply lanes extending from said drag plate, a dividing horn interconnecting adjacent sides of said supply lanes, a pair of deflecting gates, means pivotally supporting one end of each of said gates on said drag plate in a rest position with said gates 40 having a parallel relationship spaced apart a distance less than the diameter of two of said objects but greater than
